WATER SKI SLED

William Vanis, 2400 Greenbay Road, Evanston, Ill.

Filed July 7, 1961, Ser. No. 65,832

Term of patent 14 years

(Cl. D71—1)

Fig. 1.

FIG. 1 is a top plan view of a water ski sled showing my new design, the opposite side thereof being substantially the same in appearance;

FIG. 2 is a side elevational view thereof with one ski element in a depressed position;

FIG. 3 is a bottom plan view; and

FIG. 4 is a front perspective view thereof.

I claim:

The ornamental design for a water ski sled, substantially as shown and described.
